UNITED STATES PATENT OFFICE.

EDWARD MELCHERS, OF TOLEDO, OHIO.

DESIGN FOR A PICTURE-HOOK.

SPECIFICATION forming part of Design No. 33,550, dated November 13, 1900.

Application filed October 12, 1900. Serial No. 32,897. Term of patent 14 years.

To all whom it may concern:

Be it known that I, EDWARD MELCHERS, of Toledo, county of Lucas, and State of Ohio, have invented a certain new and original Design for a Picture-Hook; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention has reference to a novel design for a picture-hook adapted to be fastened to the plastered walls of a house.

In the drawings, Figure 1 is a perspective view showing the design. Fig. 2 is a front elevation, and Fig. 3 a side elevation, of the same to more fully disclose the design.

The essential feature of my new design comprises a straight flattened shank formed into a hook at its lower end and divided at its up-

per end into a plurality of diverging sections or arms bent angularly to form spurs.

Referring more particularly to the drawings, 1 is the straight flattened shank, formed with the hook 2 at its lower end. 3 represents the diverging arms, bent angularly at 4 to form the spurs 5, which terminate in sharpened points 6. The shank 1 and the diverging arms 3 are, as shown, arranged in the same plane.

Having thus described my new and original design, what I claim, and desire to secure by Letters Patent, is--

The design for a picture-hook, substantially as shown and described.

In testimony that I claim the foregoing as my own I affix my signature in presence of two witnesses.

EDWARD MELCHERS.

Witnesses:

CARL H. KELLER,
JAMES W. CORWIN.
